(57) **CLAIM**

The ornamental design for a roller assembly for lawnmower,
as shown and described.

DESCRIPTION

FIG. 1 is a top, right side perspective view of a lawnmower
where the roller assembly is attached to a lawnmower, the
broken-line disclosure of the lawnmower is being shown for
illustrative purposes only and forming no part of the claimed
design;

FIG. 2 is a top, right side perspective view of a lawnmower
before previous casters ave been removed and the roller
assembly is attached.

FIG. 3 is a front view of the lawnmower with the roller
assembly attached.

FIG. 4 is a top, right side perspective view of the roller
assembly according to FIG. 1 with a break out section to
show the structure of the roller;

FIG. 5 is a top plan view of the roller assembly; according
to FIG. 1;

FIG. 6 is a right side elevational view of the roller assembly
according to FIG. 1; and,

FIG. 7 is a left side elevational view of the roller assembly
according to FIG. 1.
